UNITED STATES PATENT OFFICE.

WILLIAM F. LAUTENSCHLAGER, OF CINCINNATI, OHIO, ASSIGNOR TO LORENZ MUTHER, OF NEWTON, MASSACHUSETTS.

PRESSING DEVICE FOR FOLDING MACHINES.

Application filed December 1, 1922. Serial No. 604,846.

This invention relates to a pressing device for folding machines and although capable of general use, is designed with particular reference to a folding machine of the construction shown in U. S. Letters Patent No. 1,399,264, issued to me on December 6, 1921.

In the use of folding machines for folding the edges of leather and other sheet material, great difficulty has heretofore been experienced in folding the convexly curved edges of the work and so far as I am informed no machine has heretofore been produced which will accomplish generally satisfactory results in this respect. In all machines adapted for this kind of work, it is essential that means be provided for turning the edge to be folded up or over into a position where it may be engaged by the pressing means to be pressed into a cemented relation with the reverse side of the body portion of the material without crumpling or wrinkling the turned over fold. The folding of straight edges is a comparatively simple problem and no great difficulty has been met with in this respect. The same is true in folding those edges which are concave since those edges must be slit which greatly facilitates the folding operation. In folding convexly curved edges of the work, however, the turning up of the edge to be folded causes a fullness to appear in that edge which assumes a wavy appearance which on curves of small radii develops into pleats. In consequence of this fullness, there is a natural tendency for the turned up or over edge to resume its original position and straighten out just as soon as it leaves the turning or folding means, and when the pressing means operates the edge is either straightened out or crushed and wrinkled which requires that portion to be refolded by hand.

Further complications are introduced because the convexly curved edge after it leaves the turning member travels in a direction different from that taken by a straight edge. The latter travels along the normal line of feed of the machine but the convexly curved edge proceeds along a line inclined away from the line of feed and sometimes when the curve is of small radius along a line approximately perpendicular to it.

As a result of the foregoing conditions, the various pressing means heretofore provided in the different machines in use have proved entirely inadequate to produce perfect fold-

ing on those edges of the work which are curved convexly.

The primary object of my invention is the provision of pressing means, applicable to folding machines in general, which is equally well adapted for folding all kinds of work whether the edges be straight or curved either convexly or concavely.

Other objects of the invention will be more specifically set forth and described hereinafter.

In the drawings illustrating the preferred form of my invention, Figure 1 is a partial end elevation of a folding machine of the type illustrated in the Letters Patent hereinbefore referred to, having a pressing means constructed and operated in accordance with the present invention applied thereto; Fig. 2 is a cross sectional view on line 2-2 in Fig. 1, looking downwardly; Fig. 3 is a side elevation as viewed from the operator's seat of the end of the lower arm of the machine showing the pressing means in relation to the work-support and fold-turning means; Fig. 4 is a side elevation of the pressing means; Fig. 5 is an end elevation of the same; Fig. 6 is a front elevation of the same; Figs. 7, 8 and 9 are diagrammatic views showing various stages in the operation of the pressing means upon a turned up edge.

In the drawings is shown a small portion of the machine described in said Letters Patent issued to me December 6, 1921, merely for the purpose of illustrating the application of my invention thereto, and for convenience the reference numerals used in said Letters Patent are retained for such parts of said machine as are shown here. Referring to Figures 1 and 2, 10 designates the frame, 11 the lower arm, and 25 a convexly curved work-support secured by screws 23 to the lower arm 11. The folding instrumentalities shown comprise a gauge 30 for guiding the work through the machine, a fold turner or plow 31 for turning over the edge to be folded, a feed-bar 32 for feeding the work in a step-by-step manner forwardly in conjunction with a feed-roll 33, and 36 a lower fixed knife-block. For a more detailed description of the foregoing parts and their mode of operation reference may be made to said Letters Patent.

The novel features of my invention reside in the provision of pressing means

adapted for folding convex edges even where the fullness causes the edge to assume a position perpendicular to the normal pressing surface. In the preferred embodiment 5 of my invention, I provide means normally advanced for engaging the upturned edge to be folded in such manner that it is laid over upon the body portion of the material smoothly without crushing or wrinkling. 10 In the form shown in the drawings, the pressing member which is mounted on the rod 160 is provided with a body portion 300 having a pressing surface 302 parallel to the curved surface of the work-support 25. 15 On one side the body portion 300 is cut away to receive a member 306 which is pivotally mounted at its upper end on a pin 308 secured in the body portion. The lower end of the member 306 is in the form of a 20 rectangular finger with a pressing surface 312 which is in alignment with the pressing surface 302 on the body portion 300 when the said member is retracted into the slot 310 formed in the face of the said body 25 portion. The member 306, is, however, normally held in an advanced position by any suitable means, which will permit its retraction into the slot 310 when sufficient pressure is applied, such as, a light helical spring 30 314 mounted in a suitable bore back of the said member. The slot 310 should be of such depth that the full retraction of the member 306 will bring the pressing surface 312 of said member into exact alignment with the pressing surface 302 of the main body 35 portion. The advanced movement of the said retractable member may be limited by squaring its upper corner at 316 to engage the shoulder 318 on the body portion. In order to facilitate the formation of pleats 40 in the folded over portion on convex curves the retractable member 306 may be cut away at 320 adjacent the body portion to form a recess. 45

In folding convexly curved edges, the pressing device should be turned axially toward the operator in order to strike the edge radially as it leaves the turning device or plow in a lateral direction. In my patent 50 hereinbefore referred to, the rod 160 is provided with a finger piece for turning it when necessary to turn the pressing device nearer to the plow to act upon convexly curved edges in a radial direction. This turning 55 means, however, is not shown herein but said patent may be referred to for a more complete description of it and its operation. In Figure 2, however, the position of the pressing surface when the pressing member 60 is rotated on its axis is shown in dotted lines. This rotation to a certain extent destroys the parallel relation between the curved surface of the work-support and the curved pressing surface but this discrepancy is taken 65 care of by the extra thickness of the folded

edge on convex curves due to the presence of pleats. At the same time the rotation of the pressing device brings the recess 320 into radial relation with the convex edge and results in the formation of pleats which 70 are radial and uniform.

In the operation of my invention, the pressing device is normally in a raised position with the member 306 held in an advanced position as shown in Fig. 4 by the 75 spring 314, the pressing surface of the member 306 being more nearly vertical than the pressing surface 302 of the main body portion of the device. In Figs. 7 to 9 inclusive is illustrated the various stages of a pressing operation. In Fig. 7 the material 324 is shown arranged on the curved work-support 25 with its edge 326 turned upwardly. In this figure the edge is shown not in the position in which it comes from the plow, 80 which would be approximately vertical, but in the position in which the edge would be thrown on a convex curve by the fullness thereof. The pressing device is shown in its normal position at the beginning of the 85 downward stroke. In this position it will be noticed that the pressing surface 302 of the main body portion is very nearly perpendicular to the edge 326 in which case the pressing device in its downward movement would tend to crush and crumple the edge rather than to turn it over smoothly upon the material. The member 306, however, is advanced, so that its pressing surface 312 is more nearly vertical than the pressing surface 302, in consequence of which the advanced member strikes the edge 326 more 90 nearly flatwise and thereby turns it on the folded line as a pivotal line. In Fig. 8 the pressing device is shown in the midway position, having moved about one-half of its 95 normal stroke. In this position the fold 326 is shown as being bent downwardly toward the body portion 324 of the material and the resistance offered thereby has caused 100 the member 306 to be partially retracted against the pressure of the spring 314. In Fig. 9 is shown the parts at the conclusion 105 of the pressing operation. The fold 326 has been laid smoothly upon the body portion 110 324 of the material and the member 306 has been entirely retracted into the slot 310 so that the pressing surface of the member 306 is in alignment with the pressing surface 302 of the main body portion, the two pressing 115 surfaces constituting the entire pressing surface of the device.

In folding convex curves, the amount of rotation of the pressing device is at all times within the control of the operator so 120 that a radial adjustment can be secured irrespective of the radius of the curve or the direction in which it leaves the turning device. The rotation of the pressing device, 125 however, brings it nearer to the plow or 130

turning device thereby lessening the flattening of the fold due to the fullness.

Although I have shown and described my invention as applied to the machine of my 5 said patent of December 6, 1921, it is to be understood that it is not to be limited to that particular application since it is capable of broad use and of application generally to folding machines of various construction.

10 It is also capable of embodiment in other forms of construction than that herein shown without departing from the spirit thereof and within the scope of the following claims.

15 What I claim is:

1. A pressing device for folding machines having a main pressing member and a member retractable within said main pressing member but normally advanced for engaging 20 the upturned fold approximately flatwise; said device being rotatable to press convexly curved edges radially.

2. A pressing device for folding machines having a main body with a pressing 25 surface and a retractable member pivotally mounted on said main body and normally in advanced position for transversely engaging the upturned fold in advance of the said body portion; said device being rotatable to press convexly curved edges radially.

3. A pressing device for folding machines having a main body portion with a 35 pressing surface, a retractable member pivotally mounted on said body portion and resilient means for holding it in an advanced position to engage the upturned fold transversely and flatwise and turn it into position to be pressed down by said body portion; said device being rotatable to press convexly curved edges radially.

4. A pressing device for folding machines having a pressing surface a portion of which is normally advanced toward a vertical plane for engaging the upturned edge 45 of the material to be folded transversely and more nearly flatwise; said advanced portion being retractable at the conclusion of the pressing operation into alignment with the remainder of the said pressing surface; said device being rotatable to press convexly curved edges radially.

5. A pressing device for folding machines having in combination a main body 55 portion provided with a pressing surface and a slot therein, a member pivotally mounted in and retractable into said slot and resilient means for holding said member in an advanced position; said device being rotatable to press convexly curved edges radially.

6. A pressing device for folding machines having, in combination, a main body portion provided with a pressing surface, a 65 retractable member pivotally mounted on

said body portion and having a pressing surface which is in alignment with the pressing surface on said body portion when said member is in a fully retracted position and resilient means for holding said member in an advanced position; said device being rotatable to press convexly curved edges radially. 70

7. A rotatable pressing device for folding machines having a main pressing member 75 and a retractable member normally advanced for engaging the upturned fold approximately flatwise; said retractable member being cut away adjacent the main member to permit pleats to form in the folding of convexly curved edges.

8. A rotatable pressing device for folding machines having a main body with a pressing surface and a retractable member 85 pivotally mounted on said main body and normally in advanced position for engaging the upturned fold in advance of the said body portion; said retractable member being cut away adjacent the main member to permit pleats to form in the folding of convexly curved edges. 90

9. A rotatable pressing device for folding machines having a main body portion 95 with a pressing surface, a retractable member pivotally mounted on said body portion and resilient means for holding it in an advanced position to engage the upturned fold flatwise and turn it into position to be pressed down by said body portion; said retractable member being cut away adjacent 100 the main member to permit pleats to form in the folding of convexly curved edges.

10. A rotatable pressing device for folding machines having a pressing surface a portion of which is normally advanced toward a vertical plane for engaging the upturned edge of the material to be folded more nearly flatwise; said advanced portion being retractable at the conclusion of the pressing operation into alignment with the remainder 110 of the said pressing surface and being provided with a recess to permit pleats to form. 105

11. A pressing device for folding machines having in combination a main body portion provided with a pressing surface and 115 a slot therein, a member pivotally mounted in said slot and resilient means for holding said member in an advanced position; said device being rotatable at the will of the operator without interfering with the operation of the machine. 120

12. A pressing device for folding machines having, in combination, a main body portion provided with a pressing surface, a retractable member pivotally mounted on 125 said body portion and having a pressing surface which is in alignment with the pressing surface on said body portion when said member is in a fully retracted position and resilient means for holding said member in an 130

advanced position; said device being rotatable to press convexly curved edges radially and being provided with a recess permitting radial pleats to form in said work.

13. A pressing device for folding machines having, in combination, a main body portion with a pressing surface parallel to the work to be pressed, said pressing surface having a cut-out portion transverse to the normal line of feed, a retractable pressing member pivotally mounted in said cut-out portion at the end thereof nearest the body of the work, means for holding the free end of said member normally downwardly in position to engage flatwise the upturned edge to be folded before the main body portion engages said edge in the pressing operation, said holding means being compressible to permit said member to be retracted in said cut-out portion during the pressing operation and means within the control of the operator for rotating said device to press curves of small radii.

14. A pressing device for folding machines having a main body portion with a pressing surface, a retractable member pivotally mounted on said body portion and a spring for holding it in an advanced position to engage the upturned fold transversely and flatwise and turn it into position to be pressed down by said body portion; said device being rotatable to press convexly curved edges radially.

15. A pressing device for folding machines having in combination a main body portion provided with a pressing surface and a slot therein, a member pivotally mounted in said slot and a spring for holding said member in an advanced position; said device being rotatable to press convexly curved edges radially.

In witness whereof, I hereunto set my hand this twenty-fourth day of November, 1922.

WILLIAM F. LAUTENSCHLAGER.
